UNITED STATES PATENT OFFICE.

PEDER O. PEDERSON, OF ALBION, WISCONSIN.

AUTOMATIC GRAIN-SCALE.

SPECIFICATION forming part of Letters Patent No. 362,992, dated May 17, 1887.

Application filed September 16, 1886. Serial No. 213,746. (No model.)

To all whom it may concern:

Be it known that I, PEDER O. PEDERSON, a citizen of the United States, residing at Albion, in the county of Jackson, in the State of Wisconsin, have invented certain new, useful, and important Improvements upon a Machine for Automatically Weighing and Registering Grain, which may be used upon a thrashing-machine or in an elevator or grainery, of which the following is a specification.

Figure 1 represents an external appearance of the machine; Fig. 2, an end elevation in section, and Fig. 3 a side elevation of the interior thereof.

15 The registering mechanism is within the box *a*. Grain enters the machine through the funnel *b*. On the front end of the box are openings in a hinged door, which can be swung open by unlatching the hook *c*, which it is necessary to do in order to reset the registering-wheels. Through these openings are seen the figures upon the registering-wheels *d d' d''*, representing units, tens, and hundreds. The scale-beam *f* projects through the top of the box near its front end. This beam has a movable weight, *f'*, that, when adjusted thereon to the figures showing the quantity of grain to be weighed in each bin, is secured in place by the set-screw *f''*. Whenever the scale-beam swings from one side of the box to the other, as shown by dotted lines in the drawings, Fig. 2, a pawl, *g*, moves the unit-wheel forward one tooth. Spring-pawl *2 3 4* prevent any backward movement of the wheels *d d' d''*; but as there is no novelty in the registering mechanism it will not be further described.

There are two V-shaped grain-bins, *h h'*. They slide in grooves in the vertical supports *k k'* on either side of the bins. These balanced bins are suspended from the oscillating shaft *m* by means of ropes *n*, which are fastened to

the half pulley-wheels *o o'*, that are rigidly secured to and turn with the shaft. The inside of each bin, at the bottom, has an opening, *p*, which corresponds in shape to the opening *p'* in the partition between the bins. The emptied grain falls into a chute, *q*, and thence into measures; or bags may be hung upon the rollers *r r'* by means of the pins *5 6*. These rollers are connected together by a crossed rope, *s*, and are turned partly over by the lever *t*, which movement lets the bags be disengaged easily from the pins.

When the grain enters the hopper underneath the funnel, it falls upon the spout *u*, rigidly attached to the oscillating shaft *v*. This shaft is turned by means of the pin *w* on the half pulley-wheel *o'*, working in the forked lever *w'*.

The operation is as follows: When a bin is full or has the number of pounds of grain in it indicated by the scale-beam, it sinks down and discharges itself, turning the main shaft *m* and raising the empty bin. The turning of the shaft shifts the position of the scale-beam. 60 The pin *w* on the half pulley-wheel within the forked lever *w'* turns the shaft *v*, changes the position of the grain-spout *u*, and causes the grain to flow into and fill the empty bin. 65

What I claim as new, and desire to secure by Letters Patent, is—

1. The combination of the two bins *h h'* with the oscillating shafts *m v* and the scale-beam upon the shaft *m*, as described.
2. The combination of the shafts *m v* with the scale-beam *f*, half-wheel *o'*, and the pin and forked lever *w w'*, substantially as described.

PEDER O. PEDERSON.
